UNITED STATES PATENT OFFICE.

SCOTT A. HARRIS, OF PAWHUSKA, OKLAHOMA.

BREAST-STRAP.

1,191,418.

Specification of Letters Patent. Patented July 18, 1916.

Application filed February 18, 1914. Serial No. 819,505.

To all whom it may concern:

Be it known that I, SCOTT A. HARRIS, a citizen of the United States, residing at Pawhuska, in the county of Osage and State 5 of Oklahoma, have invented certain new and useful Improvements in Breast-Straps, of which the following is a specification.

This invention relates to an improved breast strap, and the principal object of the 10 invention is to provide a breast strap with an improved means for adjustably connecting the two sections of the strap, the connecting pin being so constructed that the entire strain is not brought against the 15 lower edge of the opening in which the pin is placed thereby preventing danger of the opening being torn.

Another object of the invention is to provide the lower section of the breast strap 20 with an improved construction so that the connecting pin will be securely held in place and so that the section of the breast strap will not be very quickly worn out due to frictional engagement with the breast yoke.

25 This invention is illustrated in the accompanying drawings wherein—

Figure 1 is an elevation of the improved breast strap mounted upon a breast yoke, one end of which is shown; Fig. 2 is a longitudinal sectional view taken along the line 2—2 of Fig. 1; Fig. 3 is an elevation of the metallic liner which is mounted in the eye of the lower section of the breast strap. This breast strap comprises the upper and 30 lower sections 10 and 11 which are adjustably connected together by means of a pin carried by the lower section and passed through a selected opening formed in the upper section. The lower section is mounted 35 upon the breast yoke 12 and is held in place by means of the usual securing member 13 whereas the upper section is carried by the collar which passes through the loop 40 14 of the upper section.

45 The upper section 10 is formed from a strip of leather which is double intermediate its length and sewed together as shown in Fig. 1. The stitches do not extend the full length of the upper section but terminate 50 short of the upper end so that the loop 14 through which the collar passes will be formed. Openings 15 are formed in the upper section and extend longitudinally of the upper section. In the drawing there has 55 been shown four of these openings, but it is of course obvious that the number will be

changed according to the size of the breast strap. Protecting plates or washers 16 which are formed of any suitable material such as leather or light metal are secured 60 to the upper section by means of suitable rivets as shown and surround the openings 15 to protect the upper section of the breast yoke from being worn through by frictional engagement of the head formed upon 65 the coupling pin carried by the lower section.

The lower section is formed from two leather strips 17 and 18 which are placed one upon the other and doubled to provide a loop through which the breast yoke passes. 70 The metallic liner 19 fits in the loop of the lower section and is held in place by means of the side flanges 20 which engage the side edges of the two strips 17 and 18 and thus prevent the liner from moving transversely 75 through the loop. The coupling pin has its shank 21 positioned as shown at Figs. 1 and 2 and secured by rivets 22. The stem 23 which passes through openings 15 is curved as shown in Fig. 2 so that when the arms 80 of the head 24 engage the washer 16, the curved stem will only engage the lower edge portion of the opening 15 through which it passes. By having this stem curved, instead of being straight, there is thus accomplished 85 a two point contact which prevents the stem from striking squarely against the lower end of the opening 15 thus preventing any danger of the upper section being torn through from one opening to another. 90

95 This breast yoke is operated in a very simple manner. The lower section is permanently connected with the breast yoke and the upper section is mounted upon the collar. After the harness has been placed upon the horse and the horse attached to the vehicle, the head 24 is passed through one of the openings 15 and its sections are then turned to extend parallel as shown at Fig. 2 with the head 24 engaging one side of the 100 upper section and the curved stem engaging the lower end of the opening at the opposite side of the upper section. This breast yoke can therefore stand a great deal of strain without breaking since the strain is 105 not placed entirely upon the lower end of the opening, but is evenly distributed between the edge of the opening engaged by the stem and the body portion of the upper section where it is engaged by the arms of the head 110 24. A tug could be connected with a swing-tree by means of the same construction, the

tug having its free end provided with the eyes and the engaging elements which carry the stems 23 being mounted upon the ends of the swingletree.

5 What is claimed is:

- A breast strap comprising an upper section having openings formed therein, a lower section formed from a strip doubled intermediate its length to provide an eye
10 having the end portions of the strip extending therefrom, and a coupling pin provided with a shank secured between the end portions of the strip forming the lower section and having a longitudinally curved stem
15 arranged to extend from the shank through one of the openings of the upper section

and terminating in a cross head arranged to project upon opposite sides of the stem and of the openings through which the stem passes and to engage the face of the upper section to releasably connect the upper and lower sections, the arrangement being such that the upper section extends substantially parallel to the ends of the strip forming the lower section. 20

25 In testimony whereof I affix my signature in presence of two witnesses.

SCOTT A. HARRIS.
